[57] **ABSTRACT**

Liquid hydrocarbons containing minor amounts of surface active, higher alkyl trimethyl ammonium salts are surprisingly resistant to forming water in oil emulsions and microbiological degradation. Detergent range alkyl trimethyl ammonium chlorides of limited hydrocarbon solubility are especially useful as antihaze and/or antimicrobial agents for heating oils. The water solubility of the new oil additives unexpectedly facilitates their bactericidal effectiveness. Furthermore, antihaze activity of these additives is uniquely unaffected by polar oligomeric additives such as cold flow improvers and detergents also present in the oil products.

HIGHER ALKYL TRIMETHYL AMMONIUM SALT LIQUID HYDROCARBON COMPOSITIONS

FIELD OF THE INVENTION

This invention relates to liquid hydrocarbons containing minor amounts of surface active, higher alkyl trimethyl ammonium salts. In one aspect, this invention relates to hydrocarbon, oils, i.e., fuels, containing higher alkyl trimethyl ammonium salt additives. In another aspect, this invention relates to middle distillate fuels having higher alkyl trimethyl ammonium chlorides together with polar oligomeric additives.

One useful aspect of the invention relates to the suppression of water-in-oil emulsion forming tendencies of liquid hydrocarbons by the use of minor amounts of said additives. In this respect, the inhibition of haze formation in heating oils containing cold flow improver additives is of particular interest. Another useful aspect of the invention is the inhibition of microbiological deterioration, particularly of bacterial attack, of hydrocarbons.

PRIOR ART

Higher alkyl trimethyl ammonium salts, especially the chlorides, are known surfactants with high microbiocidal activity. Their synthesis and properties are described in considerable detail in a recent monograph entitled, "Cationic Surfactants," edited by Eric Jungermann, published by Marcel Dekker, Inc. in New York in 1970. However, to date such salts were considered as useful components mainly in systems containing a major amount of water. In contrast, the present invention describes compositions comprising such salts with major amounts of liquid hydrocarbons.

Unlike higher monoalkyl trimethyl ammonium salts, the higher dialkyl dimethyl ammonium salts are known oil soluble surfactants and microbiocides. For example, U.S. Pat. Nos. 3,008,813 and 3,265,474 to J. R. Siegel and U.S. Pat. 3,346,353 to B. R. Strickland and L. Berkowitz all describe hydrocarbon oils which contain higher dialkyl dimethyl ammonium salts, especially chlorides to improve their water tolerance. Other inventions involving similar compositions containing oil soluble quaternary ammonium salts are described in U.S. Pat. Nos. 3,033,665, 3,158,647 and 3,397,970. There are also many general statements about the usefulness of quaternary ammonium salts in oil products. The latter invite experimentation with such salts in general. However, in toto the prior art teaches that in oil applications, the higher dialkyl rather than monoalkyl compounds are useful.

In the present invention, it was found, in contrast to the teaching of the prior art, that liquid hydrocarbon compositions containing higher monoalkyl trimethyl ammonium salts have highly unexpected useful properties. Although most of these monoalkyl salts such as the chlorides have a limited oil solubility, this does not adversely affect their usefulness. Surprisingly, oils containing these salts have properties which are absent in similar compositions containing the oil soluble salts of the prior art.

The effect of monoalkyl trimethyl ammonium salts is particularly unique in hydrocarbons containing high molecular weight polar organic compounds. Such polymers in general facilitate the formation of water in oil emulsions, stabilize such emulsions and counteract the effect of antihaze agents. It was surprisingly found that

the additives of the present invention, in contrast to quaternary ammonium salts having two or three higher alkyl groups, are effective in the presence of polar oligomers such as a low molecular weight ethylene-

5 vinyl acetate copolymer. This effectiveness of the salts of the present invention in the presence of such polymers is very important since such polymers are increasingly used, for example, to improve the cold flow properties of oils and to provide detergency to hydrocarbon 10 systems. In the presence of such polymers, known antihaze agents often stabilize rather than break water in oil emulsions. During the handling of fuels, emulsion stabilization results in water pickup from tank and ship bottoms. The hazy oil so obtained has an adverse appeal to the customer when contrasted with the clear oil he expects.

15 The microbiocidal effect of monoalkyl trimethyl ammonium salts of low oil solubility in the present hydrocarbon compositions is surprisingly advantageous. This effect is associated with the preferential water solubility of such salts. Water solubility is important since the microbial degradation of oil, which is primarily due to bacterial activity, occurs at the water-oil interface.

20 25 Since the amount of water, petroleum products are exposed to, is relatively small, preferential water solubility of our oil bactericides means concentration at their site of action rather than complete loss through selective extraction.

30

SUMMARY OF THE INVENTION

In the present invention it has been found that liquid hydrocarbons containing minor amounts of surface active, C_8+ higher alkyl trimethyl ammonium salts have a surprising resistance to forming water in oil emulsions and to microbial degradation. The compositions of the present invention were distinguished over known hydrocarbon oil compositions containing higher dialkyl dimethyl ammonium salts by comparative evaluations 35 of their antihaze and antibacterial properties. The present compositions were found to be particularly unique in retaining their haze resistance even in the presence of polar oligomeric additives, such as ethylene-vinyl acetate copolymers.

40 45 50 The essential minor higher alkyl trimethyl ammonium salt components of the present compositions are characterized as follows: $[R\ N^+(CH_3)_3] Q^-$, wherein R is a C_8 to C_{40} open chain aliphatic hydrocarbon group such as alkyl, alkenyl and alkynyl. The alkyl group may be interrupted by arylene groups such as phenylene, by amino, sulfide and oxide groups. As such the alkyl group may be branched or straight chain. A straight chain structure is preferred. Branching is preferably limited to methyl groups. The open chain alkyl group may have a saturated cyclic component such as cyclohexylene and cyclopentylene. The number of carbon atoms in the aliphatic group is preferably between C_8 and C_{25} , more preferably between C_{10} and C_{18} . Salt mixtures having components with aliphatic groups of different carbon atoms are surprisingly advantageous.

55 60 65 The aliphatic group is preferably saturated, i.e., an open chain alkyl radical such as shown by the formula $[C_nH_{2n+1}N^+(CH_3)_3] Cl^-$. Preferred alkyl radicals have a completely non-branched straight chain structure or an alphanethyl substituted normal alkyl structure as shown by the following salt formula:

and

wherein n , m and l are numbers in accord with the number of carbons in the aliphatic group. These three formulae are of course related to the more general earlier formula. The R group of the earlier formula equals the $\text{C}_n\text{H}_{2n+1}$, $\text{CH}_3(\text{CH}_2)_n$ and the $\text{CH}_3(\text{CH}_2)_l\text{CH}_2(\text{CH}_3)$ of the present formula. Accordingly, the preferable number ranges are 8 to 40 for n , 7 to 39 for m and 6 to 38 for l . In the case of unsubstituted normal alkyl groups, the most preferred number of carbon atoms is 14. However, it is surprisingly advantageously to employ a mixture of n-alkyl compounds derived from coconut oil. Similarly, the α -methyl branched product is preferably derived from a mixture of detergent range olefins.

In general, the higher alkyl group of the present salts is the hydrophobic part of a surfactant molecule. As such it is an oil soluble group; nevertheless its size, i.e., carbon number, is limited by a limited water solubility requirement for the overall molecule. On the other hand, this group must be large enough to assure some oil solubility. The water versus oil solubility ratios, i.e., coefficients, are very important in determining the demulsifying and bactericidal properties of the salts in hydrocarbon systems. The optimum properties for a practical use will, of course, also depend on the hydrocarbon, e.g. on its paraffinic versus aromatic character.

The Q^- anion of the salts of the present invention includes negatively charged, nonradical species inorganic and organic in character. Inorganic anions include halides such as chloride, bromide, fluoride; phosphates such as polyphosphates; phosphite; sulfate and nitrite. Organic anions include carboxylates, having 1 to 30, preferably 1 to 18, carbon atoms, such as acetate, neotridecanoate, ethylenediamine tetraacetate; organic phosphate and phosphine anions such as C_2 to C_6 dialkyl dithiophosphate, phosphate, phosphite and phosphonate; C_1 to C_{30} hydrocarbon sulfonate such as methanesulfonate, benzenesulfonate, tetrapropylsulfonate; C_1 to C_{12} alkyl sulfate such as methylsulfate.

Chloride anions are most preferred because of the ease of preparation of the chloride salts and their high effectiveness. The Q^- anion may be a complex anion formed by combining one of the simple anions such as the chloride with a metal salt or an acid such as boron fluoride or acetic acid. In general, monovalent anions are preferred.

The ammonium salt component is usually present in the liquid hydrocarbon at a concentration of 0.0001 to 1 percent, preferably 0.0005 to 0.1 percent, most preferably, 0.001 to 0.004 percent. The preferred concentration of the salt is somewhat dependent on the major hydrocarbon component used and the properties desired. The above preferred concentrations are mainly recommended for heating oils resistant to water haze. Another important property of similar oil compositions is resistance to microbiological degradation. Other properties include reduced corrosivity, detergent action, etc.

Such ammonium salts especially the higher n-alkyl trimethyl ammonium chlorides, are commercially

available. Salts containing a mixture of alkyl groups are especially widely used because they can be manufactured from readily available agricultural products, such as coconut oil, tallow oil, soya oil. The preparation of such chlorides, their compositions and suppliers are described in the monograph on "Cationic Surfactants" cited hereinabove.

The major hydrocarbon components of the present compositions are preferably hydrocarbon oils of natural origin such as crude petroleum and distillate fuels. The petroleum distillates have preferable boiling ranges between 75° and 900°F. Such products include gasolines, jet fuels, diesel fuels, heating oils, lubricating oil, transformer oils. Distillate fuels boiling in the range between about 250° and 750°F. are particularly preferred. Heating oil and diesel fuel are specific choice hydrocarbons. They are described in ASTM Specifications D-396-48T and D-975-53-T. Most specifically, Grades 1 and 2 heating oils are used. Jet fuels are other specific examples. Typical aviation turbojet fuels are described by U.S. Military Specifications and referred to as JP-4, JP-5, JP-6, etc.

The polar oligomeric additives of the present compositions are optional minor components. Such additives are described in detail in U.S. Pat. Nos. 3,008,813; 3,265,474; 3,346,353 and 3,397,970 which were referred to earlier. These additives preferably contain a major proportion of nonpolar hydrocarbon groups such as alkyl, alkylene, phenyl, naphthyl, and a major proportion of polar atoms such as oxygen and chlorine. The oxygen is preferably present in ester groups. A preferred polar oligomer is the copolymer of ethylene and vinyl-acetate described by M. J. Wisotsky, A. E. Kober and I. A. Zlochower in the "Journal of Applied Polymer Science" in Volume 15 on pages 1,737 to 1,742 in 1971. Such polymers have a preferable molecular weight range of 400 to 20,000. Increasingly more preferred molecular weight ranges are from 500 to 10,000, from 500 to 5,000, from 1,000 to 3,000.

These polymeric additives are preferably employed in concentrations ranging from about 0.001 to 2 percent, more preferably 0.001 to 0.15 percent, most preferably 0.005 to 0.05 percent.

In middle distillate fuels, these polymers are mainly employed to secure the desired degree of fluidity at low temperatures. In general, such additives have a polymethylene chain interrupted by aliphatic groups having substituents containing oxygen, chlorine and aromatic radicals. Such polymers can be prepared by copolymerizing a major amount of ethylene with minor amounts of an ethylenic monomer having substituents containing the above radicals. Such substituted ethylenes are vinyl esters of C_2 to C_{18} monocarboxylic acids, acrylate, maleate and fumarate esters of C_1 to C_{18} alcohols, vinyl chloride, C_1 to C_{16} vinyl ketones. The copolymerization is usually catalyzed by free radical type chemical or irradiation initiators.

The claimed compositions have a unique resistance to water haze formation and microbial degradation due to the presence of the higher alkyl trimethylammonium salt component.

The haze behavior is usually determined in the Warping Blender Test. In this, five milliliters of water and 500 milliliters of the liquid hydrocarbon composition are mixed with a high speed rotational mixer for 2 minutes. The mixture is then allowed to separate into a water and a hydrocarbon phase. Separation, i.e., the

rate of the breakup of the emulsion, is measured spectrophotometrically. The amount of light transmitted through a sample from the top of the mixture is indirectly related to haze.

The microbial degradation of hydrocarbons is mainly due to bacterial attack by gram negative organisms at water-oil interfaces. Certain bacteria readily metabolize straight chain hydrocarbons. These hydrocarbons are present in petroleum and hydrocarbon fuels. The higher the percentage of paraffinic hydrocarbons, the faster the microbial degradation. Fast microbial degradation is concurrent with a rapid increase of the number of bacteria in the water phase. The inhibition of microbial degradation is indirectly measured by determining the concentration of additives which will inhibit the multiplication of bacteria or kill the microorganisms. Usually, serial dilution tests are carried out using different additive concentrations. A known concentration of a bacterial culture is an aqueous nutrient medium which is overlaid with oil. Bacterial counts are made at various intervals after the inoculation.

It was found in the present invention, that the above-described higher alkyl trimethylammonium salts are surprisingly useful as demulsifiers for water in hydrocarbon systems particularly as antihaze agents for hydrocarbon fuels and petroleum crudes. Most specifically, such salts are useful antihaze agents in middle distillate fuels such as heating oil and diesel fuel.

It was also found that the said higher alkyl trimethyl ammonium salts are unexpectedly useful to prevent the microbial degradation of liquid hydrocarbons when in contact with water. These salts are particularly effective bacteriostatic and bactericidal agents for petroleum and products derived therefrom such as distillate fuels. They are specifically useful as heating oil, diesel fuel, jet fuel and crude oil bactericides.

As such the present invention provides methods for preventing and breaking water in oil emulsions especially haze in the systems described. It also provides a method for similarly preventing and inhibiting microbial, particularly bacterial, attack and deterioration. When used in a process of dehazing oils and/or inhibiting their microbial deterioration, the present aliphatic hydrocarbyl trimethyl ammonium salts may be added to the liquid hydrocarbon as such or in the form of a concentrate solution in polar organic solvents. Exemplary solvents are alcohols such as isopropanol, ethylene glycol; ketones such as methyl isobutyl ketone; esters such as ethyl acetate, tricresyl phosphate, etc. These salts may also be used in composite multipurpose formulations with other oil additives such as flow improvers, antioxidants, etc.

EXAMPLES

A. Effectiveness of Surface Active Quaternary Ammonium Compounds as Demulsifiers in the Waring Blender Test

The antihaze effectiveness of various quaternary ammonium chlorides in oil was tested in a Waring Blender Test. In this test the oil was mixed with one percent water and a certain amount of the ammonium chloride

in the blender at 10,000 rpm for 2 minutes to produce the test emulsions. The stability of the emulsions was then determined by a periodical measurement of their light transmittance. The light transmittance is directly related to the clarity of the resulting oil.

EXAMPLE 1

Comparison of the Effect of Various Types of Quaternary Ammonium Chlorides in the Presence and in the Absence of a Highly Branched Ethylene - Vinyl Acetate Copolymer

The haze behavior of an oil was tested in the presence and in the absence of a polar copolymer flow improver. Representative higher mono-, di- and trialkyl derivatives of ammonium chlorides were used to determine the effect the type of surface active structure has on the haze behavior.

The oil was a heating oil containing 90 percent alkyl, 20 percent aryl and essentially no olefinic hydrogens by proton magnetic resonance (pmr) spectroscopy.

The flow improver composition consisted of about 52 percent ethylene - vinyl acetate copolymer and 48 percent light mineral oil. The copolymer had a number average molecular weight of about 2,605 by vapor phase osmometry. Its pmr spectrum showed a ratio of about 6.8 for the ethylene versus vinyl acetate derived structural units. For every one hundred methylene atoms in the backbone of the copolymer there were about 10-12 methyl branches. This copolymer was prepared by copolymerizing ethylene and vinyl acetate using an ethylene pressure of 950 psig at a temperature of about 150° with di-tertiary butyl peroxide initiator.

The results of the Waring Blender Tests are shown in Table I. Two sets of light transmittance values are tabulated. The first set of values were determined in tests using the base oil alone. The second set shows the behavior of the same base oil containing the polymer.

The data show that while the higher mono- and dialkyl quaternary ammonium chlorides accelerate emulsion breaking in the absence of the flow improver, the higher di- and trialkyl quaternary chlorides stabilize the emulsion when the polymeric additive is present. Only the higher alkyl trimethyl derivatives are effective demulsifiers in both presence and absence of the polar copolymer.

Of the two compounds of Group I in the Table the C₁₄-alkyl derivative is more effective than the C₁₈ compound although the latter is more surface active.

The higher dialkyl derivative in Group II, dicoco dimethyl ammonium chloride is an outstandingly effective demulsifier in the absence of the copolymer but an emulsion stabilizer in its presence.

The compound of the third group, i.e., the higher trialkyl methyl derivative has no significant beneficial action in the absence of the polar copolymer and an adverse effect in its presence.

In conclusion, these data show that certain water soluble higher alkyl trimethyl quaternary chlorides are effective demulsifiers for water in oil systems in the presence of oil soluble surfactants such as an ethylene-vinyl acetate copolymer.

^a One percent water and 10 ppm of the test compound were added to 500 ml portions of the oil. The resulting compositions were then mixed in the blender at 10,000 rpm for 2 minutes. The solubility of the emulsions was determined by a periodical measurement of their light transmittance using a Bausch and Lamb spectrophotometer.

^b One ml of isopropanol was added to dissolve the quaternary ammonium compound.

^c Dicoco dimethyl ammonium chloride. Although the average number of carbon atoms is about 12 in the higher alkyl chains, these chains consist of a mixture of 47% C_{12} , 18% C_{14} , 9% C_{16} , 8% C_{18} , 10% C_{16} , 5% C_{18} alkyl and 5% C_{18} alkenyl groups which were derived from coconut oil.

EXAMPLE 2

Effectiveness of Various Monoalkyl Trimethyl Ammonium Chlorides in the Presence and in the Absence of a Slightly Branched Ethylene - Vinyl Acetate Copolymer

The haze behavior of an oil used in the previous example was tested in the presence of various monoalkyl trimethyl ammonium chlorides as demulsifiers. As a polar oligomer again an ethylene-vinyl acetate copolymer was used. This copolymer again had a molecular weight range in the 2,000's. Also, this copolymer had a high ethylene-vinyl acetate ratio, i.e., about 8. However, this polymer had only about 4 methyl branches per 100 methylene groups. As a consequence, this copolymer has more crystalline character and lower solubility. As such it is dissolved in a naphthenic solvent and employed as a concentrate. The other significant difference is the absence of crosslinking in this copolymer as opposed to the minor amount of gel in the co-

sequent to the mixing this control is almost completely clear just like most of the oils containing the test compounds. The demulsifying effect of the test compounds in this case is best observed shortly after mixing. The one hour data show that at the higher concentration all these quaternaries acted as effective demulsifiers (No. 1-5).

Looking at the relative effectiveness of the higher mono-n-alkyl compounds tested, it is interesting to observe that the monococo trimethyl ammonium chloride (No. 3) which contains a mixture of detergent range n-alkyl groups is more active than pure compounds of similar structure (Nos. 1 and 2). The sec.-alkyl compounds consisting of mixtures of α -methyl branched alkyl trimethyl ammonium chlorides (Nos. 9 and 10) showed a behavior similar to their straight chain isomers (No. 3).

It seems that it is advantageous to use higher monoalkyl quaternaries containing a mixture of alkyl groups in the maximum activity range rather than a compound having a single alkyl group of optimum activity.

TABLE II

EFFECT OF LONG CHAIN ALKYL TRIMETHYL AMMONIUM CHLORIDES ON THE HAZE BEHAVIOR OF HEATING OIL CONTAINING 0.04% LESS BRANCHED ETHYLENE-VINYL ACETATE COPOLYMER IN THE WARING BLENDER TEST

^a Monococo trimethyl ammonium chloride having alkyl groups derived from coconut oil. (Table I, C).

^b Mixtures of homologous compounds of structure $[C_nH_{2n+1}CH(CH_3)N^+(CH_3)_3]Cl^-$.

^c The sec.-alkyl groups have the following composition: 2% C_{16} ; 23% C_{11} ; 23% C_{12} ; 24% C_{13} ; 25% C_{14} ; 3% C_{15} .

^d The sec.-alkyl groups have the following composition: 1% C_{16} ; 18% C_{15} ; 17% C_{16} ; 16% C_{17} ; 16% C_{18} ; 14% C_{19} ; 13% C_{20} ; 5% C_{21} .

polymer of the previous example. These differences are largely due to the lower temperature of polymerization of the present product, i.e., about 90°C.

The results of the Waring Blender Test in the presence of 0.04 percent of this copolymer are shown in Table II. The data show that the control base oil containing this less branched copolymer alone has a higher resistance to haze (No. 6). After 24 hours standing sub-

EXAMPLE 3

Comparison of the Effect of Higher Mono- and Di-Alkyl Ammonium Chlorides in the Presence of Two Ethylene - Vinyl Acetate Copolymers Having Different Degrees of Branching

The haze behavior of the oil used in the previous examples was tested in the presence of the slightly

branched copolymer of Example 2 and the highly branched copolymer of Example 1. As demulsifiers detergent range alkyl trimethyl ammonium chloride and dialkyl dimethyl ammonium chloride compounds were used. The results are shown by Table III.

The test data on compositions containing no quaternary additive (Nos. 1-3) show that, in contrast to the highly branched copolymer of Example 1 (No. 3), the slightly branched copolymer of Example 2 (No. 2) has no adverse effect on the emulsification tendency of the base oil (No. 1). The transparency data of the first seven hours after the mixing show that the addition of the monoalkyl ammonium compounds helps to demulsify in the presence of both copolymers (Nos. 4-9). In contrast, the dialkyl compound shows no beneficial effect in the presence of either of the copolymers (Nos. 11 and 12) although it is effective in their absence (No. 10). In general, the effects are more pronounced and the differences are more significant in the presence of the highly branched copolymer.

The C_{12} - C_{16} monoalkyl derivatives of trimethyl ammonium chlorides were found to be effective in the previous examples as antihaze additives in the Waring Blender Test in oils containing various ethylene-vinyl

acetate copolymer flow improvers. In the present example, the effectiveness of monococo trimethyl ammonium chloride was further examined in a heating oil in the presence of an acrylate copolymer as shown in Table IV. As shown by the Table, this oil contained cyclohexyl amine antioxidants and an acrylate copolymer multipurpose additive. The presence of the acrylate was of particular interest since it has an adverse effect on haze formation (No. 1 versus Nos. 6 and 8).

The data show that both the base oil (No. 1) and the oil containing dicyclohexyl amine (No. 4) are highly responsive to the quaternary antihaze additive (Nos. 2 and 5). The oils additionally containing the acrylate copolymer (Nos. 6 and 8) are also improved by the quaternary compound (Nos. 7 and 9). It is noted that after 20 one hour the transparency readings become somewhat

Effectiveness of Monococo Trimethyl Ammonium Chloride as a Dehazing Agent in the Presence and in the Absence of an Acrylate Copolymer

erratic in the presence of the acrylate (Nos. 6-10). This is apparently due to the slower separation. The data in these cases probably also depend on the region of the liquid sample taken from a tall cylinder. Nevertheless, overall the conclusion with regard to the effectiveness of the quaternary compound is very well supported.

^a Used as a 50% isopropanol solution

^b Composed of 75% light cracked oil and 25% virgin gas oil

^c A mixture of methyl cyclohexyl amines

^d Dicyclohexyl amine

^e A multipurpose additive consisting of an acrylate copolymer which is described in Table V

EXAMPLE 5

Effectiveness of Monococo Trimethyl Ammonium Chloride as a Dehazing Agent in Various Heating Oils in the Presence of an Acrylate Copolymer

In this example the effect of monococo trimethyl ammonium chloride is further illustrated in various heating oils. These oils also contained antioxidants and an acrylate copolymer as a multipurpose additive. The results of the tests are shown by Table V.

The light transmittance data show that in each case the addition of the quaternary compound increased the transmittance, i.e., reduced haze. The difference in the haze behavior of the corresponding oils with and without the quaternary additive is quite definite throughout the 24 hour test period.

The table also provides some additional information on the effect of the acrylate copolymer. This multipurpose additive, when used in combination with cyclohexylamine antioxidants, does again contribute to the haze problem like some other polar polymers do. Its adverse effect, however, is overcome by the addition of the higher monoalkyl quaternary compound.

As a hydrocarbon phase for utilization by these bacteria a petroleum middle distillate blend consisting of 73 percent diesel fuel and 27 percent water white kerosene was employed. The diesel fuel component contained about 80 percent paraffinic and 20 percent aromatic components.

As the water phase a P₁ basal salt medium was used. This medium was similar to the one reported by E. J. McKenna in a doctoral dissertation of the University of Iowa, entitled "Effect of Hydrocarbon Structure on Mechanisms of Microbial Alkane Metabolism," published by University Microfilms, Inc. as No. 66-7218 in Ann Arbor, Michigan.

The tests used a high oil to water ratio to better simulate oil tank conditions. One hundred ml oil, 4 ml basal salt medium and 1 ml aqueous suspension of the bacterial inoculum in a 0.2 M phosphate buffer of pH 6.8 was used in each test. In each case, the aqueous phase, containing 700×10^7 viable organisms, was placed in a serum bottle of 2 in. diameter and 4 in. high. Then the desired amount of test compound was added as a 0.1 ml solution. Onto the top of the final water solution, 100 ml of the oil was layered.

B. Effectiveness of Biologically Active Quaternary Ammonium Compounds as Oil Microbiocides in Bactericidal Tests

The microbiocidal effectiveness of various quaternary ammonium chlorides was tested against various bacteria metabolizing hydrocarbons. These bacteria generally belonged to gram negative bacterial strains. Some of the bacteria were actually isolated from heating oil tank bottoms. All the bacteria utilized the paraffin components of uninhibited distillate fuels.

EXAMPLE 6

Effectiveness of Quaternary Higher Monoalkyl Versus Dialkyl Ammonium Chlorides as a Middle Distillate Bactericide

The quaternary higher mono- and dialkyl ammonium chlorides derived from coconut oil were compared for their bactericidal effectiveness against a mixture of three gram negative strains. These strains were isolated from two home oil heater tank bottoms.

The test bottles were closed with rubber stoppers and 50 vented through a No. 18 gauge hypodermic needle. They were incubated for 7 days under stationary conditions on a laboratory bench at about 24°C. Thereafter, 1 ml was withdrawn from the interface region of each bottle, using a 1 ml tuberculin syringe fitted with a No. 18 gauge needle. A 0.1 ml sample of each of 10^{-5} , 10^{-7} and 10^7 dilutions were spread over a nutrient agar plate, which was subsequently incubated for 72 hours. Thereafter, the number of viable cells was determined and tabulated as shown in Table VI.

60 The sharp reduction of viable cells by the application of the experimental and control compounds showed a generally high effectiveness. The lower cell count in the mixture containing 500 ppm monococo trimethyl ammonium chloride (No. 1) than in the similar mixture containing the dicoco compound (No. 2) indicates that the higher monoalkyl salts are surprisingly more effective than the higher dialkyl derivatives. Similarly the higher monoalkyl compound having a branched alkyl chain is more effective than the known oil bactericide control.

TABLE VI

2 EFFECTIVENESS OF HIGHER MONOALKYL AMMONIUM CHLORIDES AS PETROLEUM BIOCIDES FOR OIL
 3 TANK BOTTOM APPLICATIONS IN A SIMULATED LABORATORY TEST

Sequence No.	Quaternary Ammonium Chloride Experimental Bactericides Formula and Solution Employed	Composition	Number of Viable Cells x 10 ⁷ in Solutions Containing Various Bactericide Concentrations, ppm, after 7 Days Plus 72 Hours Incubation		
			0	500	1,000
1	$[\text{Coco}-\text{N}^+(\text{CH}_3)_3]\text{Cl}^-$	Monococo trimethyl ammonium chloride having n-alkyl groups as described in Table I	13,350	5	3
2	$[(\text{Coco})_2\text{N}^+(\text{CH}_3)_2]\text{Cl}^-$	Dicoco dimethyl ammonium chloride having n-alkyl groups as described in Table I	13,350	26	4
Control	75% i-propanol				
3	$[\text{C}_n\text{H}_{2n+1}\text{CHN}^+(\text{CH}_3)_3]$ CH ₃	Alpha methyl branched n-alkyl trimethyl ammonium chloride composed of a 1 to 1 mixture of the two compositions described under No. 4 and 5 of Table XI	13,350	2	0
50% i-propanol					

EXAMPLE 7

Effectiveness of Quaternary Higher Monoalkyl Versus
Dialkyl Ammonium Chlorides as a Crude Oil
Bactericide Against Anaerobic Bacteria

The effectiveness of several higher monoalkyl trimethyl ammonium chlorides was determined against sulfate reducing, anaerobic bacteria in comparative tests with a commercial higher dialkyl dimethyl ammonium chloride.

The bacteria were from the Borregas Field, Kingsville, Texas. The test system was a 3.5 percent NaCl sulfate reducing broth bacteria culture containing 100,000 bacteria per milliliter. Different concentrations of the ammonium chlorides were added to vials containing the broth medium. The media were then inoculated. The vials were incubated at 30°C. and observed at intervals for evidence of bacterial growth. The results are shown by Table VII.

The data show a complete growth inhibition for a minimum of 14 days by all the quaternary ammonium chlorides at the 50 ppm concentration level. At 25 ppm the higher monoalkyl compounds still show a complete inhibition (Nos. 1 and 2). Surprisingly, the control higher dialkyl derivative (No. 3) shows no complete control.

EXAMPLE 8

Effectiveness of Quaternary Higher Monoalkyl Versus
Dialkyl Ammonium Chlorides as Crude Oil
Bactericides Against Aerobic Bacteria

The comparative effectiveness of a pair of ammonium chlorides was determined against aerobic bacteria from Block 73, Louisiana. The test system was a 3.5 percent NaCl aerobic broth bacteria culture containing 100,000 bacteria per milliliter. The test procedure was the same as in the previous example. The results are shown by Table VIII.

TABLE VII

Sequence No.	Quaternary Ammonium Chloride Tested	Observation Period, Days	Growth (+) or No Growth (-) in the Presence of Various Concentrations (ppm) of Test Compounds				
			0	12.5	25	50	100
1	$[\text{C}_{12}\text{H}_{25}\text{N}^+(\text{CH}_3)_3]\text{Cl}^-$	4	+	-	-	-	-
		7	+	+	-	-	-
		14	+	+	-	-	-
2	$[\text{C}_{14}\text{H}_{29}\text{N}^+(\text{CH}_3)_3]\text{Cl}^-$	4	+	-	-	-	-
		7	+	-	-	-	-
		14	+	-	-	-	-
3 Control	$[(\text{Coco})_2\text{N}^+(\text{CH}_3)_2]\text{Cl}^-$ ^a	4	+	-	-	-	-
		7	+	+	-	-	-
		14	+	+	+	-	-

^a Composition as described in Example 1.

TABLE VIII

Seq. No.	Structure of Test Compound	Observation Period, Days	Growth (+) or No Growth (-) in the Presence of Various Concentrations (ppm) of Test Compound				
			0	12.5	25	50	100
1	$[\text{C}_{14}\text{H}_{29}\text{N}^+(\text{CH}_3)_3]\text{Cl}^-$	1	+	+	-	-	-
		7	+	+	+	-	-
		14	+	+	+	-	-
2 Control	$[(\text{Coco})_2\text{N}^+(\text{CH}_3)_2]\text{Cl}^-$ ^a	1	+	+	+	-	-
		7	+	+	+	+	-
		14	+	+	+	+	-

^a As described in Example 1.

The data show that, surprisingly, about 50 ppm monoalkyl compound (No. 1) was required for complete inhibition while 100 ppm dialkyl derivative (No. 2) was necessary for the same effect.

EXAMPLE 9

Effect of Higher n-Alkyl Trimethyl Ammonium Chlorides as Middle Distillate Bactericides

The comparative bactericidal effectiveness of trimethyl ammonium chlorides having higher n-alkyl groups of different chain length was investigated in a P₁ basal salt medium overlayed with diesel fuel. As test organisms, two gram negative strains isolated from tank bottoms of a home oil heater were used (Nos. 1 and 2). Also employed were two other gram negative bacterial strains (Nos. 3 and 4) also utilizing diesel fuel. The organisms were grown in the presence of 10 and 100 ppm of each salt. In each test, 10 ml of basal salt medium overlayed with 0.1 ml. i.e., 1 percent of diesel fuel was used. After a 48 hour growth period, samples were streaked on nutrient agar plates and incubated for 48 hours at 30°C. to determine the viability of the test organisms. The results are shown in Table IX.

The data show that all the quaternary ammonium chlorides examined show activity at the 100 ppm concentration level at least against one of the organisms employed. In these tests, the maximum activity was shown by the n-hexadecyl derivative. However, the data indicate that the optimum chain length is dependent on the bacterial strain used.

It should be noted that in commercial oil bactericide use, prevention of troublesome bacterial growth rather than total inhibition is sufficient. For this reason and due to the excess basal salt layer, the concentration of the salt additives may be smaller in field use than in these laboratory tests.

EXAMPLE 10

Effect of Straight Chain and Branched Higher Alkyl Trimethyl Ammonium Chloride as Middle Distillate Bactericides

The comparative effectiveness of several higher 1-alkyl and 2-alkyl trimethyl ammonium chlorides was investigated using the test procedure described in the previous example. However, in this test only one gram negative bacterial strain was used. This strain was isolated from the heating oil tank bottoms of a home. The test mixtures were sampled after 24 and 48 hours. The results are shown in Table X.

The data show that in general, the mixtures of homologous alkyl compounds (Groups II and III) showed better inhibition than the pure alkyl compounds (Group I). Furthermore, the detergent range alkyl compounds (Nos. 3 and 5) were more active than those having even higher alkyl groups (Nos. 4 and 6). Interestingly, no difference was observed in the activity of the 1- and 2-alkyl detergent range compounds (Nos. 3 and 5). Both the completely straight chain (No. 3) and the alpha methyl branched compounds completely inhibited bacterial growth for 48 hours at 20 ppm.

TABLE IX

[Effect of higher n-alkyl trimethyl ammonium chlorides on gram negative bacteria utilizing diesel fuel]

Sequence number	R group of [RN ⁺ (CH ₃) ₃]Cl ⁻ salt	Growth (+) and no growth (-) at various concentrations ^a (p.p.m.) of salt							
		Bacterial isolate 1		Bacterial isolate 2		Bacterial isolate 3		Bacterial isolate 4	
		10	100	10	100	10	100	10	100
1	n-C ₁₄ H ₂₉	+	+	+	+	+	-	+	-
2	n-C ₁₆ H ₂₉	+	+	-	-	+	-	+	+
3	n-C ₁₈ H ₂₉	+	+	+	-	+	+	+	+
4	n-C ₁₂ H ₂₅ -	+	-	+	-	+	-	+	+

^a Besides using 100 and 10 p.p.m., tests were also carried out in the presence of 1 p.p.m. of the salts. However, at the latter concentration, no inhibition was observed.

TABLE X

EFFECT OF HIGHER 1-ALKYL AND 2-ALKYL TRIMETHYL AMMONIUM CHLORIDES ON GRAM NEGATIVE BACTERIA UTILIZING DIESEL FUEL

Group No.	Sequence No.	R-Groups of [R-N ⁺ (CH ₃) ₃]Cl ⁻ Salt	Growth (+) and No Growth (-) at Various Concentrations (ppm) of Salt After 24 and 48 Hours						
			20 ppm	100 ppm	500 ppm	24	48	24	48

	6	CH ₃ (CH ₂) ₁₃₋₁₈ -CH(CH ₃) ^{-c,e}				+	+	+	+

^a Monococo trimethyl ammonium chloride as described in Table I.

^b Soya trimethyl ammonium chloride having primarily n-alkenyl groups of the following composition: 90% C₁₆; 10% C₁₈.

^c A mixture of homologous compounds of structure [CH₃(CH₂)_nCH(CH₃)-N⁺(CH₃)₃]Cl⁻.

^d The composition of the 2-alkyl groups is described in Table II under footnote c.

^e The composition of the 2-alkyl groups is described in Table II under footnote d.

EXAMPLE 11

Effect of n-Dodecyl Trimethyl Ammonium Chloride as a Jet Fuel Bactericide

The effect of various concentrations of n-dodecyl trimethyl ammonium chloride on the growth of various bacterial strains utilizing jet fuel was studied.

Five contaminated jet fuel samples were used to isolate five bacterial strains by the spread plate technique. The isolated strains were further purified and then characterized. The cell morphology and the gram-stain characteristics of the strains are shown by Table XI.

The five bacterial isolates were routinely maintained on nutrient agar slants by weekly transfers. The above five cultures (24 hr. old slant cultures) were inoculated into culture tubes containing 7 ml of sterile nutrient broth and incubated at 30°C. under stationary conditions for 24 hours. At the end of the incubation period, contents from each tube were transferred under sterile conditions into sterilized centrifuge tubes. The cells were harvested by centrifugation of 10,000 RPM for 15 minutes. The cells were washed by resuspending the pellet in 10 ml sterile P₁ basal salts medium and re-centrifuged. The washed cells were resuspended again in 10 ml of sterile medium. One ml from each suspension containing in the order of 10⁸ cells/ml was used as the inoculum to each flask containing 9 ml of basal salts medium and the appropriate concentration of the inhibitors. Finally each flask was layered with 5 ml of millipore filter sterilized jet fuel. The inoculated flasks were incubated for 40 hours on a New Brunswick rotary shaker maintained at 30°C. and 250 RPM.

The growth in flasks was read at the end of seven days of incubation. At the end of 7 days of incubation, 0.01 ml of sample from each flask was streaked on nutrient agar plates and the plates were incubated overnight at 30°C. to determine the viability of the test microorganisms. The results are shown by Table XII. They indicate that, at 500 ppm, n-dodecyl trimethyl ammonium chloride completely inhibited for a week, the growth of all the bacterial strains.

TABLE XI

Sample Code	Morphological Characteristics of Jet Fuel Utilizing Microorganisms			Gram Stain

What is claimed is:

1. A liquid hydrocarbon composition containing a surface active, water soluble, saturated open chain, higher alkyl trimethyl ammonium salt, said alkyl group containing a minimum of eight carbon atoms in amounts sufficient to increase its resistance to emulsion formation and/or microbial degradation.

10 2. The composition of claim 1 wherein the liquid hydrocarbon is crude petroleum or a petroleum distillate and the higher alkyl trimethyl ammonium salt is present at concentrations between about 0.001 percent and 1 percent.

15 3. The composition of claim 2 wherein said higher alkyl trimethyl ammonium salt is a chloride in a concentration ranging from 0.001 to 0.004 percent by weight.

4. The composition of claim 3 wherein said ammonium chloride is present in a petroleum distillate.

20 5. The composition of claim 3 wherein said ammonium chloride is present in a petroleum crude.

6. The composition of claim 5 wherein said petroleum distillate is a distillate fuel boiling in the range between about 250° and 750°F.

25 7. A liquid hydrocarbon composition containing a surface active, quaternary ammonium salt of the formula

30 wherein R is a C₈ to C₄₀ saturated open chain aliphatic hydrocarbyl group and Q⁻ is an anion selected from the group consisting of halide, phosphate, phosphite, sulfate, nitrite, carboxylate, sulfonate and phosphonate, in amounts sufficient to increase its resistance to emulsion formation and/or microbial degradation.

35 8. The composition of claim 7 wherein said salt has an aliphatic R group of the formula C_nH_{2n+1} wherein n is 8 to 40.

9. The composition of claim 8 wherein the structure of the group C_nH_{2n+1} is CH₃(CH₂)_m and 40 CH₃(CH₂)₁CH(CH₃) wherein m is 7 to 39 and l is 6 to 38.

10. The composition of claim 7 wherein said salt has the group Q⁻, selected from the group consisting of halide, phosphate, phosphite, sulfate, nitrite, carboxylate, sulfonate and phosphonate.

11. The composition of claim 10 wherein the group Q⁻ is selected from the group of nonradical anions consisting of halide, phosphate, phosphite, sulfate, nitrite, carboxylate, sulfonate, phosphonate.

50 12. The composition of claim 11 wherein the anion Q⁻ is chloride.

13. The composition of claim 7 wherein the liquid hydrocarbon is crude petroleum or a petroleum distillate.

14. The composition of claim 13 wherein the petroleum distillate also contains a minor polar ethylene copolymer additive having a molecular weight range of about 400 to 20,000 said additive being derived using comonomers selected from the group consisting of vinyl esters of C₂ to C₁₈ monocarboxylic acids, acrylate esters of C₁ to C₁₈ alcohols, maleate esters of C₁ to C₁₈ alcohols, fumarate esters of C₁ to C₁₈ alcohols, vinyl chloride, C₁ to C₁₆ vinyl ketones in amounts sufficient to secure fluidity at low temperatures.

65 15. A petroleum distillate composition boiling in the range between about 250° and 750°F. having increased resistance to emulsion formation and microbial degra-

dation containing from about 0.001 to 0.1 percent of a salt of the formula

wherein n is 8 to 25, and from about 0.001 to 2 percent of a polar polymer additive having a molecular weight range of about 400 to 20,000 said additive being derived using comonomers selected from the group consisting of vinyl esters of C_2 to C_{18} monocarboxylic acids, acrylate esters of C_1 to C_{18} alcohols, maleate esters of C_1 to C_{18} alcohols, fumarate esters of C_1 to C_{18} alcohols, vinyl chloride, C_1 to C_{16} vinyl ketones, in amounts sufficient to secure fluidity at low temperatures.

16. The composition of claim 7 wherein said salt is monococo trimethyl ammonium chloride.

17. A crude petroleum or petroleum distillate composition containing as a minor component a surface active, water soluble, saturated, open chain higher alkyl trimethyl ammonium salt, said alkyl group containing a minimum of eight carbon atoms and a minor polar polymeric additive having a molecular weight range of

about 400 to 20,000 and prepared by the copolymerization of ethylene and vinyl acetate, in amounts sufficient to increase its resistance to emulsion formation.

18. A crude petroleum or petroleum distillate composition containing as a minor component in amounts up to 0.004 percent of a surface active, water soluble, saturated open chain, higher alkyl trimethyl ammonium salt, said alkyl group containing a minimum of eight carbon atoms, whereby its resistance to microbial degradation and/or emulsion formation is increased.

19. The composition of claim 2 wherein said petroleum also contains a minor polar ethylene copolymer additive having a molecular weight range of 400 to 20,000, said additive being derived using comonomers selected from the group consisting of vinyl esters of C_2 to C_{18} monocarboxylic acids, acrylate esters of C_1 to C_{18} alcohols, maleate esters of C_1 to C_{18} alcohols, fumarate esters of C_1 to C_{18} alcohols, vinyl chloride, C_1 to C_{16} vinyl ketones in amounts sufficient to secure fluidity at low temperatures.
